POWER-TRANSMITTING SYSTEM FOR
SLUSH PUMPS OR THE LIKE

Charles Martin O'Leary, Los Angeles, Calif.

Application January 9, 1947, Serial No. 721,141

11 Claims. (Cl. 103—5)

1

The present invention relates to a power transmission system particularly adapted for use in driving oil well drilling slush pumps but also useful in any connection in which it is necessary to drive two or more positive displacement pumps when they are connected in series to a single fluid discharge line.

In oil well drilling operations, slush pumps are employed to circulate the drilling fluid, or mud, through the well to facilitate the drilling operation and to remove the chips and fragments cut away by the drill bit. Because of the heavy character of the mud and the high pressures and large volumes required, particularly in deep well drilling operations, the slush pumps are required to perform under exceedingly severe conditions. As a general rule during normal drilling operations, the mud is circulated by either a single pump or two pumps connected in parallel. However, in certain instances, as, for example, when the drill pipe becomes stuck, it is necessary to compound two pumps, that is connect them in series flow of relation, in order to produce an abnormally high mud pressure. Compounding of the pumps is also required in some cases when the mud becomes aerated to such an extent that the volumetric displacement of a single pump falls below the desired value and insufficient power is available to drive it at the required higher speed against the required pressure. Steam-driven slush pumps, because of their inherent flexibility, may be successfully compounded, but the trend is away from the use of steam boilers in drilling operations and very serious difficulties have been encountered in attempting to compound internal combustion engine driven slush pumps. These difficulties are to a large extent due to the difficulty of balancing the load between two compounded slush pumps when they are driven by separate engines or by a single engine. The unavoidable overloads imposed upon one or the other of the two compounded pumps frequently result in stripping of the pump gearing or other pump failures.

Attempts have been made in the past to overcome this difficulty by driving one of the pumps through a hydrokinetic coupler or torque converter independently of the drive to the other pump. This practice is of some benefit since it increases the flexibility of the power transmis-

2

sion system and tends to reduce shock loads on the hydrokinetically driven pump. However, it does not balance the load between the two pumps and, therefore, heavy overloads are still encountered. Moreover, due to relatively wide variations in the torque load imposed on the transmission system by the slush pumps, the hydrokinetic couplers or converters are required to operate for long periods at inefficient speed ratios, with resulting overheating and injury. In addition, hydrokinetic torque converters which provide a limited variation in torque ratio at satisfactory efficiency, if designed to operate in the maximum efficient range during normal conditions, will impose an excessive stall torque upon the slush pumps at the time of starting or in the event a flow blockage occurs in the well.

Accordingly, it is the general object of the present invention to provide an improved slush pump drive mechanism suitable for use with an internal combustion engine power source in the form of either one or more engines which will overcome the above mentioned difficulties.

Another object of the present invention is to provide a slush pump drive mechanism which is peculiarly suited to the requirements encountered when two slush pumps are compounded.

Another object of the present invention is to provide, in a mechanism of the type mentioned, automatic or manually controlled means for changing the speed ratios of the slush pump drive as required.

Another object of the invention is to provide a single differential drive mechanism which may be used as a two-speed transmission for driving one or more pumps in parallel or as an automatic load-balancing drive for two compounded pumps.

Another object of the present invention is to provide, in a slush pump drive mechanism incorporating a hydrokinetic torque converter, means for automatically changing the gear ratio of the drive mechanism in such a manner as to maintain the speed ratio of the torque converter within its range of maximum efficiency and automatic means for limiting the stall torque imposed upon the slush pumps by the power transmission system.

Another object of the invention is to provide an improved form of planetary transmission characterized by its compactness and high

torque capacity and capable of use in a wide variety of power transmission systems.

Other objects and advantages of the invention will become apparent from the following specification, the drawings relating thereto and the claims hereinafter set forth.

In the drawings:

Figure 1 is a plan view showing in a generally diagrammatic manner the preferred form of the invention;

Figure 2 is an enlarged partially sectional view of the differential transmission employed in the mechanism of Figure 1;

Figure 3 is a fragmentary section taken on the line 3-3 of Figure 2;

Figure 4 is a fragmentary sectional view taken on the line 4-4 of Figure 2;

Figure 5 is a fragmentary section taken on the line 5-5 of Figure 2;

Figure 6 is a longitudinal section taken through the differentially operated control switch mechanism employed to control the speed ratios of the transmission;

Figure 7 is a transverse section taken on the line 7-7 of Figure 6;

Figure 8 is a fragmentary elevation taken on the line 8-8 of Figure 7;

Figure 9 shows the circuit connections for the control switches shown in Figure 8;

Figures 10 is a diagrammatic illustration of 30 the pneumatic control valves for the transmission mechanism and their connecting air lines;

Figure 11 shows torque and efficiency curves for the transmission apparatus; and

Figure 12 shows a modified form of transmission which may be utilized in lieu of that shown in Figures 2 and 5.

In Figure 1 of the drawings is shown a general layout of the complete drive mechanism in a more or less diagrammatic form. As there shown, the complete apparatus includes three reciprocating slush pumps 1, 2 and 3 which may be of any desired or conventional character. The pumps are connected by suitable intake piping to a sump 4 from which they draw their fluid, and are arranged to deliver fluid under pressure through the outlet pipe 5. While the pumps may be of any desired relative size, as shown the pumps 1 and 2 are larger than pump 3, this arrangement being one commonly employed in oil well drilling operations. Normally, the drilling fluid is supplied by either pump 1 or pump 2 or both of the pumps 1 and 2 connected in parallel, pump 3 being a stand-by pump for emergency use.

In accordance with the present invention, means are provided to connect any one of the pumps 1, 2 and 3 to the outlet pipe 5, both of the pumps 1 and 2 in parallel to the pipe 5, or either of the pumps 1 and 2 in series or parallel with the pump 3, to the discharge pipe 5. Thus, pump 1 is connected to the sump by an intake pipe 6 containing a shut-off valve 7; and the vertical discharge pipe 8 of the pump 1, which contains a shut-off valve 9, is connected to a branch pipe 10 of the discharge pipe 5. Pipe 10 is also connected to the discharge pipe 11 of the pump 2, the latter pipe containing a shut-off valve 12. A shut-off valve 13 controls communication between the branch pipe 10 and the discharge pipe 5. The discharge pipe 14 of pump 3 contains a shut-off valve 15 and is connected to a branch pipe 16 which, in turn, connects the inlet pipe 17 of pump 2 with the discharge pipe 5. A pair of shut-off valves 18 and 19 is positioned in branch pipe 16. Intake pipe 17 for pump 2 contains a shut-

off valve 20 between the sump 4 and the point of connection of pipes 16 and 17. The pump 3 is provided with an intake pipe 21 containing a shut-off valve 22. Between the pump 3 and the shut-off valve 22, a branch line 23 connects the intake pipe 21 with the branch pipe 10. Pipe 23 contains a shut-off valve 24. Pipe 25 connects the intake pipe 6 of pump 1 with the branch pipe 16 and contains a shut-off valve 26.

As a result of the above connections and valves, any one of the pump connections shown on the following table may be provided as required. On the table, the letter "S" in the columns under the various valves means that, for the condition corresponding to the horizontal line in which the letter appears, the valve is shut; the letter "O" indicates that the valve is open; and the absence of any letter indicates that the position of the valve is immaterial. It will be noted that the table lists pumps 1 and 3 in series and also, separately, pumps 3 and 1 in series. A duplicate listing of the series connections of the pumps 2 and 3 also appears. This is due to the fact that in the series connection, either of the two pumps may be connected in advance of the other in the direction of fluid flow.

In accordance with the present invention, the three pumps 1, 2 and 3 are connected to a novel form of power transmission, indicated generally at 27 in Figure 1, in any suitable manner, as by chain drives. Thus, the drive sprocket 28 of pump 1 is connected by means of a chain, indicated in dotted lines at 29, to a sprocket 30; the drive sprocket 31 of pump 3 is connected by means of a chain 32 to a sprocket 33; and the drive sprocket 34 of pump 2 is connected by means of a chain 35 to a sprocket 36. All three of the sprockets 30, 33 and 36 are adapted to be driven by the transmission 27, in the manner herein-after more fully pointed out. Power is supplied to the transmission 27 through a sprocket 37 which is connected by means of a chain 38 to a sprocket 39 which is fixed to the output shaft 40 of a hydrokinetic torque converter, indicated more or less diagrammatically at 41. The input shaft 42 of the converter 41 constitutes the output shaft of an internal combustion engine 43 or any other suitable source of power. The torque converter 41 is preferably provided with a differentially operated cooling fan and radiator unit 44 adapted to cool the operating liquid of the converter in approximate proportion to the rate of heat generated therein. The differential cooling mechanism per se forms no part of the present invention and, consequently, for a more detailed illustration and description thereof, reference may be had to applicant's prior copending application, Serial No. 666,626, filed May 2, 1946 now Patent Number 2,589,120, dated March 11, 1952.

The shaft 40 passes through an elongated hous-

ing 45, a portion of which is shown in the drawing, and within the housing carries a freely journaled sprocket 46 which may be connected to the shaft 49, as desired, by a pneumatically operated clutch 41. The sprocket 46 carries a chain 48 which may be connected to one or more engine-hydrokinetic torque converter units identical to the single unit illustrated in the drawings. Thus, when it is desired to utilize two or more engines to drive the slush pumps, this may be accomplished by engaging clutch 41 and supplying power to shaft 49 from additional engines.

The construction and arrangement of the transmission mechanism 27 is best illustrated in Figures 2, 3, 4 and 5. Thus, as shown in Figure 2, the input sprocket 37 is freely journaled on a tubular shaft 49 which, in turn, is journaled in casing 50 by means of roller bearings 51 and 52. The sprocket 37 is adapted to be connected to the shaft 49 by means of a pneumatically operated clutch, indicated more or less diagrammatically at 53, which may be supplied with air under pressure through a line 54 connected to a stationary manifold associated with the bearing 55 for the outer end of tubular shaft 49, in the usual manner.

The transmission 27 is of the differential type and the shaft 49 carries a sun gear 56 which meshes with a plurality of planet gears 57, each of the latter constituting one of a pair of cluster gears including a larger planet gear 58. The planet gear clusters, one of which is shown in section in Figure 2, are each journaled on coaxial pins 59 which are fixed at their opposite ends to a planet cage, indicated generally at 60. The planet cage is fixed by means of a web 61 to a shaft 62 which is journaled within the previously mentioned tubular shaft 49 and projects beyond the latter at both ends. A total of 8 sets of cluster gears is provided in the transmission in order to distribute the load over as many gear teeth as possible. As best shown in Figures 2 and 5, the planet cage 60 is in the form of an integral casting, including the web 61, a pair of parallel annular side plates 60a and 60b, which are connected together and to the web 61 by a plurality of axially extending webs 60c, and a cylindrical portion 60d which extends axially from the side plate 60b over the smaller gears of the gear clusters 58. Each of the larger gears 58 of the planet gear clusters meshes with a ring gear 63 which is fixed in any desired manner to the interior of a cylindrical housing 64 which, in turn, is connected by an end flange 65 to a tubular shaft 66.

In order to facilitate proper meshing of the cluster gears 58 with the ring gear 63, the latter preferably has a slightly floating connection to the housing 64. This may be achieved, in the manner best shown in Figure 3, by providing a plurality of external teeth 67 on the ring gear 63 which mesh somewhat loosely with internal teeth 68 formed on the interior of the housing 64. The shaft 66 is journaled by means of bearings 69 in the housing 50 of the transmission and carries at its outer end the previously mentioned drive sprocket 33 for the pump 3. The sprocket 33 is freely journaled on the shaft 66 but may be connected thereto by an air operated clutch 70 when desired, the clutch 70 being similar in construction and operation to the previously mentioned clutch 53.

The sizes of the gears 56, 57, 58 and 63 are preferably so selected as to provide a speed ratio between the shafts 49 and 62 of 2 to 1 when the housing 64 is held stationary, and selectively

operable means are provided for connecting the housing 64 to the casing 27 in order to establish the 2 to 1 drive ratio or to the planet cage 60 in order to establish a 1 to 1 drive ratio between the shafts 49 and 62.

As best shown in Figure 5, means for fixing the housing 64 to the casing 50 of the transmission comprises a plurality of clutch or brake block mechanism, one of which is shown in section in Figure 5. These mechanisms include a one-way clutch or brake block 71 which is formed of a suitable friction material and positioned within a pocket 72 formed in the casing 50. The inner surface of the brake block 71 is adapted to frictionally grip the exterior of the cylindrical housing 64. The outer sides of the pocket 72 are closed by castings 73 having flat inner surfaces 74 adapted to bear against the outer surfaces of the brake block 71. A helical spring 75 normally urges the brake block 71 in a direction to wedge it between the surface 74 and the exterior surface of the housing 64 and thus frictionally hold the housing 64 against rotation. Each casting 73 contains a cylindrical opening 76 which receives a piston 77 and which is closed at its outer end by means of a plug 78 having an air pipe connection 79 by means of which air under pressure may be supplied to the interior of the cylinder. The piston 77 is normally urged toward the plug 78 by means of a helical spring 80. A piston rod 81, fixed to the piston, carries a lug 82 which is adapted to engage the end of the brake block 71. Spring 80 normally holds the parts in the position shown, in which the lug 82 is out of engagement with the brake block 71. In this position, the spring 75 wedges the block between the housing 64 and the surface 74. However, upon application of air under pressure to the cylinder 76, the piston and, consequently, the lug 82 are shifted downwardly, as viewed in Figure 5, causing the lug 82 to engage the brake block 71 and shift it out of engagement with the housing 64. In that connection, it should be noted that housing 64 tends to rotate in a direction opposite to that of sun gear 56, i. e. clockwise, as viewed in Figure 5, and, consequently, assists the wedging action induced by spring 75. As a result, in the absence of application of air under pressure to the line 79, housing 64 is held stationary and the transmission is maintained in its 2 to 1 ratio. When the air is applied to line 79, housing 64 is free to rotate with respect to the transmission casing 50.

The supply of air to all of the cylinders 76 is preferably controlled by means of a conventional three-way valve 83, shown diagrammatically in Figure 10. The valve 83 is provided with an intake line 84 adapted to be connected with a source of air under pressure and an exhaust line 85. The valve is operated by a solenoid, indicated diagrammatically at 86, which, on energization, places the valve in the position in which it connects lines 84 and 79. When the solenoid is de-energized, line 79 is connected to the exhaust line 85.

The means for locking the housing 64 to the planet cage 59 comprises a cone clutch member 87 adapted to frictionally engage an internal cone clutch surface on the housing 64. The cone clutch element 87 is connected by a plurality of helical splines 88 to the cylindrical portion 60d of the planet cage 60. As best shown in the fragmentary sectional view of Figure 4, the helix angle of the splines 88 is such that the rotary force imposed upon the clutch element 87 by

its frictional engagement with the housing 64 tends to cause releasing movement of the clutch element, i. e. movement to the left, as viewed in Figure 2. Such release movement is assisted by a plurality of axially acting circumferentially spaced helical springs positioned between the planet cage 60 and an inwardly directed flange 89 on the clutch element 87. A portion of one of these springs is illustrated fragmentarily at 90 in Figure 2.

The means for shifting the clutch 87 into engagement with the housing 64 comprises an annular piston 91 fitted within an annular recess formed by a pair of angle members 92 and 93 carried by the end wall of the casing 50. A plurality of ball thrust bearings 94 is positioned between the piston 91 and the flange 89 of the clutch element 87. As a result of this construction, application of air under pressure to the annular cylinder through line 95 will effect engagement of the clutch 87 and thereby lock the housing 64 to the planet cage 60.

The air required to operate the annular piston 91 is supplied by a separate three-way control valve 96 which is identical in construction and mode of operation to the previously described valve 83. Thus, valve 96 is also connected to the air supply line 84 and is operated by a solenoid 97. When the solenoid 97 is energized, valve 96 connects lines 84 and 95; when it is de-energized, line 95 is connected to the exhaust line 85. As hereinafter set forth in greater detail, means are provided for controlling the operation of valve 96 either automatically or manually.

The internal shaft 62 of the transmission projects beyond the bearing 55 and has journaled on its projecting end the previously mentioned sprocket 30 which drives pump 1. The sprocket may be connected to the shaft 62, when desired, by means of a pneumatically operated clutch 98. Shaft 62 also projects at the opposite side of the transmission beyond the bearing 99 for the outer end of tubular shaft 66 and has journaled thereon the previously mentioned drive sprocket 36 for pump 2. The sprocket 36 may be connected to the shaft 62, when desired, by means of a pneumatically operated clutch 100. Shaft 62 also carries a brake drum 101 with which is associated a conventional brake band 102 by means of which the shaft 62 may be held against rotation, when desired.

As a result of the above construction, it is possible, by controlling the transmission 27 and the clutches 70, 98 and 100, to drive either pump 3 or either or both of the pumps 1 and 2 at either one of two speed ratios with respect to the speed of the input sprocket 37. Thus, when neither of the solenoids 86 and 97 is energized, the transmission 27 will be in its lower gear ratio for rotating shaft 62 in the same direction but at a speed less than that of the input shaft 49. Either or both of the pumps 1 and 2 may be connected to the shaft 62, as desired, by means of the clutches 98 and 100. When solenoid 97 is energized, the cone clutch element 87 is engaged and the transmission 27 locked in its 1 to 1 or direct drive ratio, in which the shaft 62 rotates in the same direction and at the same speed as the sprocket 37. The fact that housing 64 rotates in a counterclockwise direction when cone clutch 87 is engaged, automatically disengages the brake blocks 71. Similarly, pump 3 may be driven at a 1 to 1 speed ratio by engaging the clutch 70 and the cone clutch element 87. Pump 3 may also be driven at a higher speed ratio by

engaging the brake 102 while the brake blocks 71 and cone clutch 87 are both disengaged. The higher speed ratio in this case is in the opposite direction and will be an overdrive, and it will be necessary to disengage brake blocks 71 by energizing solenoid 86. While the shaft 66 will rotate in one direction at the 1 to 1 ratio and the opposite direction at the higher ratio, that will cause no difficulty when the transmission is utilized to drive reciprocating pumps since the direction of fluid flow is the same for both directions of rotation.

In addition to the above, an important feature of the present invention resides in the fact that the transmission 27 may be utilized to differentially drive the pump 3 with either one of the pumps 1 and 2. This is highly desirable under certain circumstances, particularly when the pump 3 is connected in series or compounded with either of the pumps 1 and 2 in order to develop an abnormally high fluid pressure for special purposes. Thus, if, for example, it is desired to compound pumps 1 and 3, clutches 98 and 70 are engaged and the brake blocks 71 and clutch 87 are disengaged. Under these circumstances, power supplied to the input shaft 49 of the transmission will be differentially transmitted to the shafts 62 and 66 and thus to the pumps 1 and 3. This arrangement has decided advantage because it insures that the torques supplied to the two pumps will always bear the same relation to each other and, consequently, the pressure rise in each of the two pumps will always bear the same relation to each other. In this connection, it is preferable to have each of the pumps develop half of the total pressure rise and, accordingly, the gear ratios of the transmission 27 and the drive connections from the transmission to the two pumps should preferably be so correlated with the effective cross-sectional areas of the pump plungers that the relation between the torque delivered to the crankshaft of one of the pumps and the cross-sectional area of the plunger of that pump is the same as the relation between the torque delivered to the crankshaft of the other pump and the cross-sectional area of the plunger of the other pump.

The different pump drive not only has the advantage that it automatically fixes and maintains the relation between the pressure rise in the two pumps a constant value, but it accomplishes that result while permitting an independent variation in the relative speeds of the two pumps. Consequently, the speeds of the pumps will automatically adjust themselves to the extent necessary to maintain the relative loads on the two pumps constant. As a result, there is no danger of either pump being subject to an overload. Where there is a difference in the sizes of the two differentially driven pumps, as in the illustrated embodiment of the invention, the smaller pump will, of course, operate at a higher speed than the larger pump and, if the pressure rise in both pumps is the same it will perform the same amount of work. It will be apparent, however, that the two differentially driven pumps may be of the same size, if desired.

The selectively operable two-speed or differential transmission may be utilized to advantage in an oil well slush pump drive which obtains its power from any suitable source. Consequently, it is unnecessary to employ a hydrokinetic torque converter or its equivalent in the drive connec-

tion to realize the advantages of the above described transmission mechanism. However, hydrokinetic torque converters are advantageous in a slush pump drive, not only because of the automatically varying torque and speed multiplication which they provide, but because they are effective to absorb shock loads and thus reduce the danger of pump failures resulting from momentary overloads, however, induced. Accordingly, in the preferred form of the invention illustrated in the drawings, the transmission 27 is driven from an internal combustion engine through a hydrokinetic torque converter.

However, torque converters have two disadvantages as applied to a slush pump drive: first, their efficiency is low except over a limited range of speed ratios; and, second, if they are so designed and connected to the slush pumps that they will deliver adequate torque at an efficient speed ratio for normal operation, they are likely to impose an excessive overload on starting or at very low speed ratios. A further feature of the present invention resides in the provision of automatic control means for the transmission 27 so constructed and arranged that it will overcome both of the above mentioned difficulties. This result is achieved by properly correlating the two speed ratios of the transmission 27 with the efficiency curve of the torque converter utilized and by automatically shifting the transmission in such a manner as to increase the speed ratio range of maximum efficiency for the complete transmission mechanism on one hand and reduce or limit the torque transmitted to the pumps on the other. The mechanism by which this result is accomplished is best shown in Figures 6, 7, 8, 9 and 10, and the performance characteristics of the mechanism are shown graphically in Figure 11.

Thus, as shown in Figure 9, the solenoid 97, which controls the operation of the valve 96, is connected in series with a pair of parallel connected switches 103 and 104 across a pair of electric supply lines 105 and 106. A manually operated switch 107 is provided for selectively connecting the line 105 to the solenoid 97 through the switches 103 and 104 or independently of the switches 103 and 104 to either the solenoid 97 or the solenoid 86, the first connection being established by engagement of the switch 107 with the contact 108, the second by engaging the switch 107 with the contact 109, and the third by engaging the switch 107 with a contact 110. As a result of these connections, when the switch 107 engages contact 108, solenoid 97 is energized when either of the switches 103 and 104 is closed. As previously indicated, the energization of solenoid 97 places the transmission 27 in its high or direct drive ratio, while de-energization of both of the solenoids 86 and 97 places the transmission in its low gear ratio.

It is necessary, in order to achieve the desired results, to correlate the two speed ratios of the transmission 27 with respect to the efficiency-speed ratio curve of the hydrokinetic torque converter employed. While such curves vary to some extent between converters of different designs, one representative curve is indicated at 112 in Figure 11. It will be noted from curve 112 that the efficiency of the torque converter is relatively high throughout a speed ratio range between .33 and .66, but drops off rapidly on either side of that range. The lower of these speed ratios, namely .33, is hereinafter referred to as the minimum efficient speed ratio of the converter, while the higher ratio, namely .66, is hereinafter referred to as the maximum efficient speed ratio. It will

be noted that for the converter whose curve is illustrated by the line 112, the ratio between the maximum and minimum efficient speed ratios is 2 to 1. Accordingly, in accordance with the present invention, the ratio between the two speed ratios of the transmission 27 is also made approximately 2 to 1. Since the high speed ratio of the transmission 27 is 1 to 1, this means that the low speed ratio should be approximately 2 to 1. In other words, in low gear, shaft 49 will rotate two revolutions for each revolution of the shaft 62. With this correlation between the speed ratios of the transmission and the maximum and minimum efficient speed ratios of the converter, it is possible to extend the speed ratio range of high efficiency by shifting the transmission from its 2 to 1 to its 1 to 1 ratio when the speed ratio of the converter reaches or exceeds its maximum efficient ratio and by returning the transmission to its lower speed ratio of 2 to 1 when the speed ratio of the converter falls below its minimum efficient speed ratio. It is also possible to reduce the stall or maximum torque delivered by the transmission and torque converter by shifting the transmission to its higher speed ratio when the transmission is in its lower speed ratio and the speed ratio of the torque converter falls below its minimum efficient ratio. In accordance with the present invention, this result is performed automatically by a differential operation of the control switches 103 and 104.

Thus, as shown in Figures 6, 7 and 8, there is provided a differential switching device comprising a base 113 which supports a pair of housings 114 and 115, which housings, in turn, support and journal five axially aligned shafts 116, 117, 118, 119 and 120, the shafts 117 and 119 being preferably journaled on antifriction bearings, indicated generally at 121 and 122, respectively. Shaft 118 carries a pulley 123 which is connected by means of a belt 124 to the input shaft 42 of the torque converter 41, as best shown in Figure 1. Consequently, shaft 118 rotates at a speed proportional to engine speed. Shaft 116 is connected by means of a flexible shaft, indicated generally at 125, to the end of shaft 62, as best shown in Figure 2. Consequently, shaft 116 is driven at a speed proportional to the speed of the output shaft 62 of the transmission 27. Shaft 116 carries a gear 128 which meshes with a gear 129 on a countershaft 130 carried by the housings 114 and 115. A gear 131 on shaft 130 meshes with a gear 132 on the shaft 120. Consequently, the shaft 120 is also rotated at a speed proportional to the speed of the output shaft 62 of the transmission.

In order to actuate the control switches 103 and 104 at the desired speed ratios, the geared speed ratio between the output shaft 62 of the transmission and shaft 116 of the differential switch actuating device is three times the speed ratio between the shaft 42 and the shaft 118. Consequently, shafts 116 and 118 will rotate at the same speed but in opposite directions when shaft 62 is rotating at one-third of the speed of shaft 42. The gears 128, 129, 131 and 132 are of such size that the shaft 120 rotates at twice the speed of shaft 116 and in the same direction. Consequently, shafts 118 and 120 will rotate at the same speed but in opposite directions when the speed of shaft 62 is one-sixth of the speed of shaft 42.

Shafts 116 and 117 are connected by an eddy current clutch, indicated generally at 133, the clutch comprising a housing 134 formed of electrically conductive material, such as aluminum or

11

copper, fixed to the shaft 117 and a multipole permanent magnet 135 fixed to the shaft 116. The shaft 116 also carries a second housing 136 which surrounds the housing 134 in the usual manner. As is well known, the eddy currents induced in the housing 134 by rotation of the multipole permanent magnet 135 create an electromotive force tending to rotate the housing 134 in the same direction as the magnet. The device, therefore, transmits a rotating torque which is proportional to the difference between the speeds of the shafts 116 and 117.

The shafts 117 and 118 are connected by a similar eddy current clutch 137 comprising a housing 138 and a multipole permanent magnet 139. Eddy current clutch 137 transmits a slipping torque from the shaft 118 to the shaft 117 which is proportional to the difference in speeds of the two shafts. Since shafts 116 and 118 are rotated in opposite directions, the forces transmitted from them to the shaft 117 by the two eddy current clutches are acting in opposite directions and tending to balance each other. However, the shaft 117 will always tend to move in the direction of rotation of the shaft having the highest speed. Therefore, when the output shaft 62 of the transmission 21 is rotating at a speed less than one-third of that of the shaft 42, the shaft 118 will be rotating at a higher speed than the shaft 116 and, therefore, will tend to rotate the shaft 117 in the direction of the arrows on shaft 118.

As best shown in Figure 8, the housing 138 has fixed thereto a pin 140, formed of insulating material, which projects through a slot 141 in the housing 115 and carries at its outer end the switch contact element 103 which is adapted to close an electrical circuit between a pair of contacts 143 and 144. The tendency of the housing 138 to rotate in the same direction as the shaft 118 under the above described circumstances holds the contact 103 out of engagement with the contacts 143 and 144. A light spring 145 also assists in holding the contact in open position. However, it will be apparent that if at any time the speed of shaft 62 exceeds one-third of the speed of shaft 42, shaft 116 will rotate at a higher speed than shaft 118 and the net force acting upon the shaft 117 will tend to rotate that shaft in the opposite direction and thereby close the switch contact 103. Consequently, the contact 103 is always open when the ratio of speeds of the shafts 62 and 42 is less than 1 to 3, and is always closed when the ratio is above 1 to 3.

Shaft 119 is similarly connected to shafts 118 and 120 by means of a pair of eddy current clutches 146 and 147, and the housing of the eddy current clutch 146 carries a pin 148 which supports the switch contact 104. It will be noted from Figure 8 that the contact 104 is reversely arranged with respect to the previously described contact 103. Consequently, when the shaft 118 is rotating at a higher speed than the shaft 120, the net force transmitted to the shaft 119 by the two eddy current clutches tends to cause the switch contact 104 to engage stationary contacts 149 and 150. Therefore, switch contact 104 is always closed when the speed of shaft 62 is less than one-sixth of the speed of shaft 42, and is always open when the speed of shaft 62 is more than one-sixth of the speed of shaft 42.

Since switch contacts 103 and 104 are connected in parallel and closure of either switch will energize the solenoid 97 of Figure 9, it will be apparent that, as a result of the above con-

12

struction, the solenoid 97 will be energized when the speed of shaft 62 is less than one-sixth of the speed of shaft 42 and more than one-third of the speed of shaft 42. Both of the contacts 103 and 104 will be opened and, therefore, the solenoid 97 will be de-energized when the speed of shaft 62 is intermediate one-third and one-sixth of the speed of shaft 42, and this will place the transmission in its low gear ratio.

The resulting performance characteristics of the drive mechanism are shown graphically in Figure 11. As there indicated, the curve 112 is the efficiency curve of the torque converter utilized in the combination, and line 151 represents the torque ratio of the converter and transmission combination when the transmission is in its 1 to 1 ratio. The lines 152 and 153 represent the efficiency and torque ratio curves for the combination when the transmission is in its low gear or 2 to 1 ratio. The differential switch operating mechanism serves to maintain the transmission in its high gear or 1 to 1 ratio at speed ratios below .16 and above .33, and to shift the transmission into its low gear ratio at intermediate speed ratios. Therefore, on starting, the torque ratio of the torque transmitted to shaft 62 will follow the line 151 down to the speed ratio of .16, at which time the transmission is shifted to its low gear ratio and the torque ratio will then jump to the torque ratio curve 153. As the speed of shaft 62 continues to increase, the torque ratio will drop off along the line 153 until a speed ratio of .33 is reached and the transmission is returned to its 1 to 1 or high gear ratio, whereupon, on further increases in the speed of shaft 62, the torque ratio will return to and follow the curve 151. If the load on the shaft 62 increases and thereby reduces the speed of the shaft below the speed ratio of .33, the transmission will be returned to its low gear ratio and the torque ratio will then follow up the curve 153 until the overall speed ratio reduces to .16.

It will be observed that by automatically maintaining the transmission in its high gear ratio at low overall speed ratios, the mechanism limits the total torque transmitted to the shaft 62, which otherwise might be excessive at exceedingly low speed ratios because of the high stall torque transmitted by the hydrokinetic torque converter. It will also be observed that by returning the transmission to its high speed ratio when the overall speed ratio reaches and exceeds .33, the mechanism extends the speed ratio range over which the torque converter operates at high efficiency.

It will be appreciated that the speed ratios at which the transmission shifts occur may be selected to give any desired performance characteristics, and that the speed ratios provided by the transmission may be altered to conform, in the manner described above in connection with the illustrated embodiment of the invention. In addition, it will be appreciated that for torque converters having different forms of efficiency curves, it will ordinarily be necessary to select different speed ratios for the shift points in order to obtain optimum results.

As previously indicated, the switch 107 may be actuated at any time to disconnect the automatic shifting control. The transmission can then be controlled manually by moving the switch arm into and out of engagement with either of the contacts 109 and 110. Thus, if desired, the pumps may be started or operated in low gear by engaging contact 109. Thereafter, the auto-

matic control may be restored to operating condition by engaging the switch arm with contact 108.

The form of transmission shown in Figure 2, if constructed to provide a 2 to 1 ratio between the shafts 49 and 62 in low gear, will provide a 1 to 2 overdrive from the shaft 49 to the shaft 66 when shaft 62 is held stationary by brake 102. Consequently, when driving pump 3, alone, the low gear ratio of the transmission is a direct or 1 to 1 drive ratio in the opposite direction and, therefore, the automatic gear shifting mechanism of Figures 6, 7 and 8 cannot be utilized.

When it is desired to differentially drive the shafts 66 and 62, switch 107 is placed in engagement with contact 110, in order to energize solenoid 86 and de-energize solenoid 97. Under these conditions, a transmission designed to provide the ratios specified above will deliver to the shaft 66 one-fourth as much torque as is delivered to the shaft 62. Consequently, it will be necessary to provide a step-down speed ratio drive between the sprocket 33 and the drive sprocket 31 of pump 3, which will give a higher speed reduction than that provided by the sprockets 36 and 34 in order to avoid driving the pump 3 at an excessive speed. The particular ratio provided will depend upon the relative sizes of the two pumps. Thus, if pumps 2 and 3 are compounded and the cross-sectional area of the plunger in pump 2 is twice that of pump 3, it will be necessary to drive pump 3 at twice the speed of pump 2. Since the sprocket 33 is already tending to rotate at four times the speed of sprocket 36 and this is more than the desired amount of increase in speed, it will be necessary to utilize twice as much speed reduction between sprockets 31 and 33 as is provided between sprockets 34 and 36.

The relatively great difference between the torque delivered to sprocket 33 and that delivered to sprocket 36 may be avoided, if desired, by utilizing the slightly modified form of transmission illustrated fragmentarily in Figure 12. The transmission of Figure 12 differs from that of Figure 2 in that the power input is connected to the planet cage and the two output shafts are connected, respectively, to the sun gear and the ring gear. With this arrangement, the output shaft which is connected to the ring gear will receive one-half as much torque as the output shaft which is connected to the sun gear, and the high gear ratios to both shafts will be overdrives.

Thus, as shown in Figure 12, planet cage 154, which is identical in construction to the planet cage 60 previously described, is connected to a tubular shaft 155 which carries a sprocket 156 adapted to be connected to the source of power. The sun gear 157 is connected to an internal shaft 158 which carries a pair of sprockets 159 and 160 which may be clutched to the shaft 158, as desired, by means of pneumatically operated clutches 161 and 162, respectively. The ring gear housing 163 is connected by means of a plate 164 to a tubular shaft 165, which carries a sliding clutch element 166 adapted to clutch a sprocket 167 to the shaft 165. A similar clutch element 168, which is splined to shaft 158, may be utilized to clutch the sprocket 167 to the shaft 158, when desired. It will be understood that sprockets 159, 160 and 167 are connected by means of chains to the three slush pumps. Preferably, the smaller slush pump, if there is any difference in size, is connected to the sprocket 167 and the two larger pumps to the sprockets 159 and 160.

The cone clutch element 169, which is similar

in construction and mode of operation to the clutch element 87 of Figure 2, has an inwardly extending flange 170 which extends to a position adjacent an annular piston 171 which operates to effect clutch engagement under the influence of air under pressure supplied through a passage-way 172 in the shaft 158.

The operation of the transmission illustrated in Figure 12 is identical to that previously described except that, when driving shaft 158, the low gear ratio is a 1 to 1 or direct drive, while the high gear drive is an overdrive. Consequently, when the automatic shifting mechanism of Figures 6 through 8 is employed, it will be necessary to reverse the contacts 103 and 104 with reference to their co-operating stationary contacts in order to effect an opening of the switches under the circumstances in which they close during the operation described above. In addition, the stationary contacts of the switches 103 and 104, instead of being connected in parallel, as shown in Figure 9, must be connected in series, and the valve 96 utilized to supply air to both the cone clutch and the brake block cylinders simultaneously. In that case, the solenoid 97 will only be energized when both of the switches are closed, and it will be de-energized when either of the switches is opened.

Both forms of transmission may be used for other purposes with advantage. Each is capable of providing two different speed ratios in one direction and a reverse drive. Three shafts are employed in each transmission: one connected to the sun gear, one to the ring gear and one to the planet cage. By driving any one of these three shafts and taking power off either of the other shafts, a wide variety of speeds is available, particularly if selectively operable brakes, such as the brakes 71 and 162, are provided on the two output shafts and clutch means are provided for selectively connecting the load to those two shafts.

While only two forms of the invention are illustrated and described herein, it will be apparent that variations in the construction and arrangement of the parts may be indulged in without departing from the spirit of the invention. Thus, the improved planetary transmissions per se are of advantage and utility in any application requiring the use of a two-speed transmission with or with the optional differential drive. In this connection, they are peculiarly suited to the heavy duty requirements of oil well slush pump, rotary table or hoisting drum drives. While the transmission may be employed without a hydro-kinetic torque converter, peculiarly advantageous results are achieved with the complete combination, including the automatic transmission shifting mechanism, which extends the effective speed ratio range of the complete drive and operates automatically to limit overloads.

What is claimed is:

1. In combination, a pair of positive displacement pumps adapted to be connected in series flow relation, a driving shaft adapted to be connected to a source of power, a pair of driven shafts, means connecting said driven shafts respectively to said pumps, and a differential gear set connecting said three shafts.
2. In combination, a pair of positive displacement pumps, a pump discharge conduit, means selectively operable to connect said pumps individually or in series flow relation to said conduit, a driving shaft adapted to be connected to a

15

source of power, a pair of driven shafts adapted to be connected respectively to said pumps, a differential gear set connecting said three shafts, and brake means on one of said driven shafts adapted on operation to hold said shaft against rotation and thus permit driving of the other driven shaft by said differential.

3. In combination, a pair of positive displacement pumps, a pump discharge conduit, means selectively operable to connect said pumps individually or in series flow relation to said conduit, a driving shaft adapted to be connected to a source of power, a pair of driven shafts adapted to be connected respectively to said pumps, a differential gear set connecting said three shafts, and selectively operable means for connecting said driven shafts in a fixed driving relation to each other.

4. In combination, a pair of positive displacement pumps, a pump discharge conduit, means selectively operable to connect said pumps individually or in series flow relation to said conduit, a driving shaft adapted to be connected to a source of power, a pair of driven shafts adapted to be connected respectively to said pumps, a differential gear set connecting said three shafts, brake means on one of said driven shafts adapted on operation to hold said shaft against rotation and thus permit driving of the other driven shaft by said differential, and selectively operable means for connecting said driven shafts in a fixed driving relation to each other.

5. In combination, a pair of positive displacement pumps, a pump discharge conduit, means selectively operable to connect said pumps individually or in series flow relation to said conduit, a driving shaft adapted to be connected to a source of power, a pair of driven shafts, means connecting said driven shafts respectively to said pumps, a differential gear set connecting said three shafts, means selectively operable to hold one driven shaft stationary to effect a drive of the other driven shaft at one speed ratio, and means selectively operable to connect said driven shafts in fixed driving relation to each other to effect a drive of said other driven shaft at another speed ratio, whereby both pumps may be driven differentially from said driving shaft or one pump may be driven at either one of two speed ratios.

6. In combination, a pair of positive displacement pumps, a pump discharge conduit, means selectively operable to connect said pumps individually or in series flow relation to said conduit, a driving shaft adapted to be connected to a source of power, a pair of driven shafts, independently disengageable power transmitting devices for connecting said driven shafts respectively to said pumps, a differential gear set connecting said three shafts, means selectively operable to hold either of said driven shafts stationary and thereby effect a drive of the other driven shaft, and means for locking said driven shafts together to effect a simultaneous drive thereof at a different speed ratio, whereby both driven shafts may be driven differentially or either driven shaft may be driven alone at either one of two speed ratios.

7. In combination, a pair of positive displacement pumps, a pump discharge conduit, means selectively operable to connect said pumps individually or in series flow relation to said conduit, a driving shaft adapted for connection to a source of power, a pair of driven shafts, means for connecting the driven shafts respectively to the pumps, and a differential gear set connecting

16

said three shafts, said differential and connecting means providing torque ratios between the driving shaft and the pumps which will enable both pumps to develop approximately the same pressure when they are connected in parallel or each pump develops approximately the same pressure rise when they are connected in series.

8. In combination, a hydrokinetic torque converter having an input shaft adapted to be connected to a source of power and having an output shaft, a two-speed ratio transmission having its input shaft connected to said torque converter output shaft and having an output shaft adapted for connection to a power consuming device, and automatic means for shifting said transmission from its lower to its higher speed ratio when the speed ratio of the converter falls below a predetermined value, said means including a power operated shifting mechanism and a speed ratio responsive control device operatively associated with the input and output shafts of the converter.

9. In combination, a hydrokinetic torque converter having an input shaft adapted to be connected to a source of power and having an output shaft, a two-speed ratio transmission having its input shaft connected to said torque converter output shaft and having an output shaft adapted for connection to a power consuming device, and automatic means for shifting said transmission from its lower to its higher speed ratio when the speed ratio of the converter increases beyond a predetermined ratio above that of maximum efficiency and vice versa when the converter ratio falls below said predetermined ratio, said automatic means being effective to shift said transmission from its lower to its higher ratio when the speed ratio of the converter falls below a second predetermined ratio below that of maximum efficiency and vice versa when the converter ratio exceeds said second predetermined ratio, said automatic means including a power-operated shifting mechanism and a speed ratio responsive control device operatively associated with the input and output shafts of the converter.

10. In combination, a hydrokinetic torque converter having an input shaft adapted to be connected to a source of power and having an output shaft, a two-speed ratio transmission having its input shaft connected to said torque converter output shaft and having an output shaft adapted for connection to a power consuming device, and automatic means for shifting said transmission from its lower to its higher speed ratio when the speed ratio of the converter increases beyond a predetermined ratio above that of maximum efficiency and vice versa when the converter ratio falls below said predetermined ratio, said automatic means being effective to shift said transmission from its lower to its higher ratio when the speed ratio of the converter falls below a second predetermined ratio below that of maximum efficiency and vice versa when the converter ratio exceeds said second predetermined ratio, said automatic means including a power-operated shifting mechanism and a speed ratio responsive control device operatively associated with the input and output shafts of the converter, the ratio between the two speed ratios of the transmission being approximately the same as the ratio between said two predetermined ratios.

11. In combination, a pair of positive displacement pumps connected in series flow relation, a driving shaft, a pair of driven shafts connected respectively to said pumps for operating the same, a differential gear set comprising a pair of

concentric gear members connected by and meshing with planet gears, and a cage member journaled coaxially with said gear members and supporting said planet gears, said three members being connected respectively to said three shafts so that the torque delivered to the two pumps is maintained in balance.
